(57) **CLAIM**

The ornamental design for a light therapy patch, as shown and described.

DESCRIPTION

FIG. 1 illustrates a front perspective view of light therapy patch;

FIG. 2 illustrates a front view of light therapy patch thereof;

FIG. 3 illustrates a back view of light therapy patch thereof;

FIG. 4 illustrates a left side view of light therapy patch thereof;

FIG. 5 illustrates a right side view of light therapy patch thereof;

FIG. 6 illustrates a top view of light therapy patch thereof;

FIG. 7 illustrates a bottom view of light therapy patch thereof;

FIG. 8 illustrates an environmental view of light therapy patch thereof; and,

FIG. 9 illustrates an in-use view of light therapy patch thereof.

The broken lines of FIGS. 1 and 2 illustrate portions of the light therapy patch that form no part of the claimed design. The broken lines of FIGS. 8 and 9 illustrate environment and form no part of the claimed design.

1 Claim, 9 Drawing Sheets
